(57) **CLAIM**

The ornamental design for a cryogenic cassette, as shown and described.

DESCRIPTION

FIG. 1 is a top perspective view of a cryogenic cassette in a closed configuration.

FIG. 2 is another top perspective view thereof in an open configuration.

FIG. 3 is a perspective view thereof with the sliding cover removed.

FIG. 4 is a top view shown in FIG. 3.

FIG. 5 is a bottom view shown in FIG. 3.

FIG. 6 is a top perspective view of the cryogenic cassette with the main body removed.

FIG. 7 is a top view thereof.

FIG. 8 is a bottom view thereof.

FIG. 9 is a top perspective view of the cryogenic cassette in a state of use, containing a cryogenic bag.

FIG. 10 is top perspective view of the cryogenic cassette positioned within a storage rack; and,

FIG. 11 is a top perspective view of the cryogenic cassette positioned within another type of storage rack.

The dashed lines in the drawings depict portions of the cryogenic cassette that form no part of the claimed design. The dot-dash lines in the drawings depict environmental subject matter and form no part of the claimed design.

1 Claim, 9 Drawing Sheets
